UNITED STATES PATENT OFFICE.

DAVID C. HOTTELL, OF NEAR MEEKER, COLORADO.

DITCHING-MACHINE.

1,317,371.

Specification of Letters Patent. Patented Sept. 30, 1919.

Application filed March 29, 1919. Serial No. 286,084.

To all whom it may concern:

Be it known that I, DAVID C. HOTTELL, a citizen of the United States, residing near Meeker, in the county of Rio Blanco and 5 State of Colorado, have invented certain new and useful Improvements in Ditching-Machines, of which the following is a specification.

This invention relates to ditching machines and more particularly to ditch cleaning machines and it has for its object the provision of an improved device of this character constructed in such manner as to provide a ditch of novel shape as will hereinafter be set forth.

Further objects and advantages of the invention will be set forth in the detailed description which now follows.

In the accompanying drawing, 20 Figure 1 is a plan view of a ditching machine constructed in accordance with the invention.

Fig. 2, is a transverse vertical section through the landside upon line 2—2 of 25 Fig. 1.

Fig. 3, is a transverse vertical section through the mold board upon line 3—3 of Fig. 1.

Fig. 4, is a side elevation looking toward 30 the mold board.

Fig. 5, is a view of the mold board illustrating the position that the mold board assumes when the ditching machine is traveling in one direction, and

35 Fig. 6, is a like view illustrating the position that the mold board assumes when the ditching machine is traveling in the opposite direction.

Like numerals designate corresponding 40 parts in all the figures of the drawing.

Referring to the drawing 5 designates the landside the rear end of which is slightly concave in form. A mold board 7 has its forward end pivotally connected to the landside by loops 8 which pass through elongated openings 9 formed in the mold board. These openings are of such size as to permit a slight rocking movement of the mold board with relation to the landside to thereby 45 permit the mold board to move vertically out of the plane of the landside in either direction, for a purpose which will be hereinafter set forth.

A clevis 10 is pivoted at 11 between ears 50 12 formed at the front end of a T-bar 13, the latter extending longitudinally along

the rear face of the land side and being secured thereto and serving to stiffen and strengthen the same as well as to provide a point of attachment for the clevis. A rod 60 14 is provided with an off-set end 15 that is adapted to engage in any one of the openings 16 of the mold board 7 and the opposite end of this rod is adapted to engage in opening 17 of the clevis 10. Links 18 and 19 65 are pivoted at 20 and 21 to the land side and mold board respectively and the link 18 is provided with a plurality of openings 22 by which said link may be adjustably connected to the link 19 through the medium 70 of a pin 23. This construction permits the mold board to be adjusted toward and from the land side to thereby adapt the device to clean ditches of varying widths. By referring to Fig. 3 it will be seen that the 75 mold board is concave in cross section and that at its front end (see Fig. 4) said mold board is tapered to form substantially straight edges 24 and 25. The land side is tapered so that at its point of attachment 80 to the mold board it is narrower than the mold board and this arrangement combined with the concavity of the mold board results in the provision of a plow-like structure which imparts a rolling movement to the 85 earth, when in action, that very effectively dislodges the dirt and discharges it from the ditch. Furthermore, the formation of a mold board of this shape and the mounting of such mold board by means of the elongated openings 9 and loops 8, provides a 90 structure which will clean a ditch of the shape illustrated at 26 in the drawing. In other words, such structure will clean a ditch 95 having a flat bottom.

Devices of this nature heretofore proposed have been adapted to clean only V shaped ditches, but by virtue of the structure herein shown and described one of the edges 24 or 25 will lie in contact with, and 100 scrape the bottom of a ditch when the machine is traveling in one direction and the other of said edge will automatically move into position to clean the bottom of the ditch when the machine is turned over and 105 is traveling in the opposite direction.

It is to be understood that the invention is not limited to the precise construction set forth, nor to the proportions illustrated, nor to the particular type of pivotal connection shown, for it is manifest that it is 110 well within the range of mechanical skill to

vary these elements without departure from the basic principle involved which is that of providing a mold board, the opposite edges of which are operable when the machine is traveling in opposite directions and which is capable of such rocking movement above and below the plane of the landside as to permit it to assume the proper position to carry out the objects set forth.

10 Having described my invention what I claim is,

1. The combination with a landside of a mold board the latter being cut away adjacent its front end to form working edges 15 which lie at an angle to the longitudinal center of the mold board and means for loosely pivotally connecting the landside and the mold board in such manner as to permit the mold board to move vertically 20 with respect to the landside in either direction, to such an extent as to cause that cut

away portion of the mold board which lies toward the bottom to lie substantially horizontal.

2. The combination with a landside, of a 25 mold board the latter being cut away adjacent its front end to form working edges which lie at an angle to the longitudinal center of the mold board, said mold board being concavo convex in cross section and being 30 wider than the landside at its point of attachment thereto, and means for holding the moldboard in varying positions of angular adjustment with respect to the landside. 35

In testimony whereof I affix my signature in the presence of two witnesses.

DAVID C. HOTTELL.
